 1 - LOWER - ALKYL - 3 - PYRROLIDYL N - LOWER -
 ALKYL - AND LOWER - CYCLOALKYL - N - ARYLCARBAMATE ANTISPASMODICS AND ANTI-
 DEPRESSIVES

Carl D. Lunsford, Richmond, Va., assignor to A. H. Robins Company, Inc., Richmond, Va., a corporation of Virginia

No Drawing. Filed Feb. 9, 1965, Ser. No. 431,440
 21 Claims. (Cl. 260—243)

ABSTRACT OF THE DISCLOSURE

The invention relates to 1-lower-alkyl-3-pyrrolidyl or 1-pyridyl-3-pyrrolidyl N-lower-alkyl- and N-lower-cycloalkyl-N-arylcaramates. The 1-lower-alkyl group has 1 to 4 carbon atoms, inclusive. The compounds are anticholinergics and antidepressives. Related compounds which are N-arylcaramates (with hydrogen being the second N substituent), N-lower-alkyl-N-lowercycloalkyl carbamates, N,N-dilower-cycloalkyl carbamates, and carbamates wherein the nitrogen atom is a part of a heterocyclic ring are also included, although not preferred.

The present invention relates to novel therapeutic compounds and is more particularly concerned with certain organic compounds having anticholinergic activity, a method for their preparation, a method of employing such compounds for purposes for exploiting their anticholinergic activity in the treatment of a living animal body, and compositions containing such an anticholinergically active compound as active ingredient.

Anticholinergic agents are useful in treating spasm of various types, such as commonly associated with spastic constipation, biliary duct spasm, arterial spasm, and similar conditions. The compounds of the invention are active anticholinergics useful for treating spasm of the type induced by acetylcholine. Employment of the anticholinergic agents of the invention in the treatment of Parkinsonism is of particular interest. Parkinsonism is a condition involving disturbance of certain brain centers, such as the mesodiencephalic activating center of the brain stem, which causes muscular rigidity and may impair normal movements and the ability to speak and write. It results from injury to basal ganglia and is frequently a sequel to virus-caused epidemic (lethargic) encephalitis. Symptoms include involuntary tremors, lack of facial expression, depressed emotional tone, and salivation.

Compounds which control these symptoms are, in general, anticholinergic agents which are capable of passing the blood brain barrier. Atropine and extracts from various species of *Stramonium flora* have long been used in treating Parkinsonism, and more recently other anticholinergic agents, such as trihexylphenidyl, procyclidine, ethopropazine, and diethazine have been so employed. The degree of utilization of any such anticholinergic agent is restricted by the undesirable side-effects which it may concurrently produce. Dryness of the mouth, blurred vision, mydriasis, epigastric distress, nausea and constipation are examples of peripheral side effects. The capacity to produce desired anticholinergic effects without the usual side effects is a highly desirable attribute of an anticholinergic. Effective agents having such an attribute

2

have long been sought without the attainment of any complete solution to the problem.

It is therefore an object of the present invention to provide novel compounds and compositions possessing valuable therapeutic properties, that is, anticholinergic activity, and a method for their preparation. Another object is to provide a novel method for the treatment of living animal and especially mammalian bodies, for purposes of combatting spasm therein. Still another object is to provide compositions which possess beneficial anticholinergic activity without deleterious peripheral activity, and which are therefore particularly useful in combatting spasm in a living animal body. A particular object of the present invention is to provide novel anticholinergic agents which are capable of passing the blood brain barrier, compositions thereof, and a method for the treatment of spasm including Parkinsonism therewith. Additional objects will be apparent to one skilled in the art and still other objects will become apparent hereinafter.

The foregoing and additional objects are accomplished by the provision of certain 1-lower-alkyl-3-pyrrolidyl N,N-disubstituted-carbamates, pharmaceutically acceptable acid-addition salts thereof, a method for their preparation, and compositions containing the same as active ingredient, and by employing such compounds and/or compositions to combat, diminish, eliminate, or ameliorate spasm in a living animal body treated therewith.

The frequency and magnitude of peripheral side effects exhibited by pre-existing anticholinergic drugs would indicate that it is extremely unusual if not impossible to isolate the desired central anticholinergic activity from concurrent undesired peripheral side effects. Unpredictably, the 1-lower-alkyl-3-pyrrolidyl N,N-disubstituted-carbamates of the invention not only exhibit a high order of central anticholinergic activity, but also extremely low peripheral side effects.

In addition to the usefulness of the 1-lower-alkyl-3-pyrrolidyl N,N-disubstituted-carbamates and their non-toxic salts as strong central anticholinergics, they may also be employed in the therapy and prevention of extra-pyramidal symptoms caused by other drugs. Moreover, the anticholinergic agents of the invention have valuable antidepressive activity.

The active anticholinergic agents of the present invention are compounds having the formula:

and pharmaceutically acceptable acid addition salts thereof, wherein R is a lower-alkyl radical having 1 to 4 carbon atoms inclusive, or pyridyl, and wherein R' is selected from the group consisting of methyl and hydrogen, a maximum of two R' being other than hydrogen.

In the preferred embodiment, A in the foregoing formula is selected from the group consisting of lower-alkyl having 1 to 6 carbon atoms inclusive and lower-cycloalkyl having 3 to 9 carbon atoms inclusive, and A' is a monocarbocyclic aryl group having a maximum of fifteen carbon atoms selected from the group consisting of phenyl, trifluoromethylphenyl, lower-alkoxyphenyl, dilower-alkyl-

aminophenyl, lower-alkylphenyl, naphthyl, and halophenyl. The substituents can be in various available positions of the phenyl nucleus and, where more than one substituent is present, can be the same or different and can be in various position combinations relative to each other. Preferably the number of substituents when present on the phenyl ring is 1 to 3, inclusive, any lower-alkyl, lower-alkoxy, and dilower-alkylamino substituents each have 1 to 4 carbon atoms, inclusive, and all ring substituents, when present, have 1 to 9 carbon atoms, inclusive.

In a second embodiment, A is hydrogen and A' has the value assigned for the first embodiment.

In a third embodiment, both A and A' are selected from the group consisting of lower-alkyl having 1 to 6 carbon atoms, inclusive, and lower-cycloalkyl having 3 to 9 carbon atoms, inclusive.

In a fourth embodiment, the radical

is a heterocyclic amine radical having 4 to 12 carbon atoms, inclusive, such as indolino, tetrahydroquinolino, phenothiazino, octahydroquinolino, morpholino, thiamorpholino, pyrrolidino, piperidino, piperazino, and lower-alkylpiperazino.

The term "lower-alkyl" as used herein includes straight and branched chain radicals of up to eight carbon atoms inclusive and is exemplified by such groups as methyl, ethyl, propyl, isopropyl, tertiary butyl, amyl, isoamyl, hexyl, heptyl, octyl, and the like. The term "lower-cycloalkyl" as used herein includes primarily cyclic alkyl radicals containing three up to nine carbon atoms inclusive and encompasses such groups as cyclopropyl, cyclobutyl, cyclohexyl, cyclopentyl, methylcyclohexyl, propylcyclohexyl, ethylcyclopentyl, propylcyclopentyl, dimethylcyclohexyl, cycloheptyl, and cyclooctyl. The "lower-alkyl" group present as the N or 1-substituent in the compounds of the invention includes only those straight and branched chain radicals containing up to four carbon atoms inclusive, and is exemplified by such groups as methyl, ethyl, propyl, isopropyl, butyl, isobutyl, tertiary butyl, and the like. When the lower-alkyl group contains more than four carbon atoms or is cycloalkyl or aralkyl, the anticholinergic activity is markedly reduced.

The compounds of the present invention are most conveniently employed in the form of water-soluble non-toxic pharmaceutically acceptable acid addition salts. The free basic compounds of Formula I may be conveniently converted into these salts by reaction of the free base with the selected acid in the presence of an aprotic organic solvent (one which is inert to the reactants and reaction product under the conditions of reaction). The acids which can be employed to prepare the preferred pharmaceutically acceptable acid addition salts are those which produce, when combined with the free bases, salts the anions of which are relatively innocuous to the animal organism in therapeutic doses of the salts, so that beneficial physiological properties inherent in the free bases are not vitiated by side effects ascribable to the anions. Appropriate acid addition salts are those derived from mineral acids such as hydrochloric acid, hydrobromic acid, hydriodic acid, nitric acid, sulfuric acid, and phosphoric acid, and organic acids such as acetic acid, citric acid, lactic acid, tartaric acid, alkyl and arylsulfonic acids, and the like. The preferred acid addition salt is the maleic acid salt.

Acid addition salts are prepared either by dissolving the free base in an aqueous solution containing the appropriate acid, or to which the acid is subsequently added, and isolating the salt by evaporating the solution, or by reacting the free base and the selected acid in an organic solvent, in which case the salt ordinarily separates directly or can be conventionally recovered by concentration of the solu-

tion or the like. Where the free basic amine is desired, this may be obtained conventionally by neutralizing the reaction product or a solution of the isolated salt with a base such as ammonia, ammonium hydroxide, sodium carbonate, or other suitable alkaline material, extracting the liberated base with a suitable solvent such as ethyl acetate or benzene, drying the extract and evaporating to dryness in vacuo or fractionally distilling, or in other conventional manner.

In their most advantageous forms for administration, the compositions of the present invention contain a non-toxic pharmaceutical carrier in addition to the active anticholinergic agent. Exemplary carriers are: solids such as lactose, magnesium stearate, calcium stearate, starch, terra alba, dicalcium phosphate, sucrose, talc, stearic acid, gelatine, agar, pectin, or acacia and liquids such as peanut oil, sesame oil, olive oil, or water.

A wide variety of pharmaceutical forms, suitable for many modes of administration and dosages, may be employed. For oral administration the active anticholinergic agent and pharmaceutical carrier may, for example, take the form of a pill, lozenge, tablet, capsule, or a liquid suspension; for parenteral administration the composition may be in the form of a sterile solution; and for rectal administration, the form may be a suppository.

The compounds of the present invention are usually administered in compositions containing from about 0.01 to 75 percent, by weight, of anticholinergic agent, preferably 0.05 to 25 percent.

The method of treating according to the invention comprises internally administering an anticholinergically effective amount of a compound of Formula I, including non-toxic acid addition salts thereof, preferably admixed with a pharmaceutical carrier, for example, in the form of any of the above-mentioned compositions, to combat spasm and symptoms thereof in a living animal body. The 1-lower-alkyl-3-pyrrolidyl N,N-disubstituted-carbamates of the present invention may be advantageously employed in a unit dosage of from 0.1 to 200 milligrams. This unit dosage may be given a suitable number of times daily so that the daily dose will vary from 0.3 to 600 milligrams. The oral unit dosage will preferably vary from about 2.5 to 50 milligrams while the parenteral dosage will usually be approximately one-half the oral dosage so that the preferred parenteral unit dosage will be about 1 to 25 milligrams. The preferred daily dosages will vary from about 7.5 to 150 milligrams (oral) to about three to 75 milligrams (parenteral). However, with this type of drug there is considerable variation in individual dosage. The invention therefore should not be limited to the exact ranges stated. The exact dosages suitable for a particular patient will of course have to be as determined and directed by the physician or veterinarian in charge. In addition, the active ingredients of the present invention or compositions containing the same may either be administered together with or include other physiologically active materials and/or medicaments, e.g., buffering agents, anti-acids, sedatives, tranquilizers, analgesics, or the like.

The high order of activity of the active agents of the present invention, as evidenced by tests in lower animals, is indicative of utility based on their valuable activity in human beings as well as in lower animals. Clinical evaluation in human beings has not been completed, however. It will be clearly understood that the distribution and marketing of any compound or composition falling within the scope of the present invention for use in human beings will of course have to be predicated upon prior approval by governmental agencies such as the Federal Food and Drug Administration which are responsible for a determination of and authorized to pass on such questions.

The anticholinergic agents of the invention, the 1-lower-alkyl-3-pyrrolidyl N,N-disubstituted-carbamates, may be conveniently prepared by reacting an alkali or alkaline earth metal alcoholate of the corresponding 1-lower-alkyl-3-pyrrolidinol with the appropriate N,N-disubstituted

(e.g., alkyl- or cycloalkyl-monocarbocyclic-aryl)-carbamyl chloride, such as methyl- or cyclohexyl-phenyl-carbamyl chloride, or other conventional methods for the production of carbamates may be employed. The metal alcoholates may in turn be produced by using as one reagent an alkali or alkaline earth metal, e.g., sodium, potassium, or calcium, or an alkali or alkaline earth metal hydride, e.g., lithium hydride, or an alkali or alkaline earth metal amide, e.g., sodium amide, or a similar alkali or alkaline earth metal reagent capable of reacting with the selected pyrrolidinol to produce a metal alcoholate. This reagent is accordingly mixed and reacted with the selected 1-lower-alkyl-3-pyrrolidinol, comprising unsubstituted or methyl- or polymethyl-1-lower-alkyl-3-pyrrolidinols, e.g., 2, 2-di-, 2-, 3-, 4-, or 5-methyl-1-lower-alkyl-3-pyrrolidinols and including polymethyl ring substituted 1-lower-alkyl-3-pyrrolidinols having more than one methyl group on the same ring carbon atoms, said pyrrolidinols being preparable as known in the art as illustrated by Lunsford U.S. Patent 2,830,997 and other sources cited therein. Representative starting methyl-1-lower-alkyl-3-pyrrolidinols are disclosed by Ryan et al., J. Org. Chem. 27, 2901-2905 (1962) and references cited therein. The alkyl- or cycloalkyl-monocarbocyclic aryl-carbamyl chlorides may for example be prepared by the reaction of phosgene with the corresponding alkyl- or cycloalkyl-monocarbocyclic aryl amine according to the procedure of Bielstein, XII, p. 428.

In greater detail, the preferred procedure for the preparation of the compounds of the invention, representatively illustrated for the 1-lower-alkyl-3-pyrrolidyl-N-alkyl- or cycloalkyl-N-monocarbocyclic aryl-carbamates, is as follows. The 1-lower-alkyl-3-pyrrolidinol or methyl-1-lower-alkyl-3-pyrrolidinol is stirred and refluxed with an equimolar quantity of an alkali or alkaline earth metal compound capable of reacting therewith to form the 3-pyrrolidinol metal alcoholate, as already mentioned above, e.g., sodium amide, in an inert organic solvent such as a hydrocarbon, e.g., benzene, toluene, xylene, or an ether, e.g., dioxane, until hydrogen or ammonia, as the case may be, is no longer evolved. To the product of this reaction is added, without isolation, the dialkyl- or cycloalkyl-monocarbocyclic-aryl-carbamyl halide, usually the chloride, preferably an equimolar quantity thereof. This addition is preferably carried out at low temperature to control the exothermic character of the reaction. Reflux is continued until the inorganic salt is no longer formed (usually several hours). The product is recovered in the normal manner. For example, the mixture is cooled, washed with water, dried over a drying agent such as anhydrous sodium sulfate, filtered, and concentrated, and the residue worked up in conventional manner, such as by fractional distillation and recrystallization. The base is converted directly to a salt by reaction with an equimolar quantity of a pharmaceutically acceptable acid. Acceptable acid addition salts include the hydrochloride, hydrobromide, p-toluenesulfonate, acetate, maleate, fumarate, sulfate, and the like. All of the acid addition salts prepared were found to be soluble in water.

The 3-pyrrolidinol used in the reaction need not necessarily be converted to its sodium or other metal salt, but may be reacted directly with the carbamyl chloride; however, the procedure described above is preferred for maximum yield in minimum reaction time.

The following preparations are given by way of illustration only and are not to be construed as limiting.

PREPARATION 1.—N-CYCLOPENTYL-N-(3-TRIFLUOROMETHYLPHENYL)-CARBAMYL CHLORIDE

N-cyclopentyl-3-trifluoromethylaniline (46 grams, 0.20 mole) was added slowly with stirring at 10 degrees centigrade to a solution of 25 grams (0.25 mole) of phosgene in 350 milliliters of chloroform. The mixture was allowed to stand overnight and refluxed for 1.5 hours and then

filtered; concentration under reduced pressure gave 54 grams of a white crystalline solid which melted at 43.5-45 degrees centigrade. This material was sufficiently pure for conversion to the 1-methyl-3-pyrrolidyl carbamate ester. Recrystallization of 10 grams from ligroin (boiling point 60-110 degrees centigrade) gave 9.8 grams of the pure carbamyl chloride, melting point 43.5-45 degrees centigrade.

PREPARATION 2.—N-CYCLOPENTYL-N-(p-CHLOROPHENYL)-CARBAMYL CHLORIDE

N-cyclopentyl-p-chloroaniline (78.4 grams, 0.4 mole) was added slowly with stirring at 10 degree centigrade to a toluene solution of 60 grams (0.6 mole) of phosgene. The resulting mixture was allowed to stand at room temperature for 1.5 hours and heated at 85 degrees centigrade for four hours, filtered, and concentrated under reduced pressure, resulting in a yield of 90 grams of the solid carbamyl chloride. This crude material was sufficiently pure for conversion to the carbamate esters. Recrystallization of the entire sample from ligroin (60-100 degrees centigrade) gave 85.5 grams of the pure, white crystalline carbamyl chloride which melted at 82-85 degrees centigrade.

PREPARATION 3.—N-METHYL-N-PHENYLCARBAMYL CHLORIDE

Using the method of Preparation 2, N-methyl-aniline was mixed and reacted with phosgene to give N-methyl-N-phenylcarbamyl chloride having a melting point of 85-86.5 degrees centigrade.

PREPARATION 4.—N-ETHYL-N-PHENYLCARBAMYL CHLORIDE

Using the method of Preparation 2, N-ethyl-aniline was mixed and reacted with phosgene to give N-ethyl-N-phenylcarbamyl chloride.

PREPARATION 5.—N-(n-PROPYL)-N-PHENYL-CARBAMYL CHLORIDE

Using the method of Preparation 2, N-(n-propyl-aniline was mixed and reacted with phosgene to give N-(n-propyl)-N-phenylcarbamyl chloride.

PREPARATION 6.—N-CYCLOPENTYL-N-PHENYL-CARBAMYL CHLORIDE

Using the method of Preparation 2, N-cyclopentyl aniline was mixed and reacted with phosgene to give N-cyclopentyl-N-phenylcarbamyl chloride having a melting point of 77.5-79.5 degrees centigrade.

PREPARATION 7.—N-CYCLOHEXYL-N-PHENYL-CARBAMYL CHLORIDE

Using the method of Preparation 2, N-cyclohexyl aniline was mixed and reacted with phosgene to give N-cyclohexyl-N-phenylcarbamyl chloride.

PREPARATION 8.—N-CYCLOHEXYL-N-(3-TRIFLUOROMETHYLPHENYL)-CARBAMYL CHLORIDE

Using the method of Preparation 2, N-cyclohexyl-3-trifluoromethylaniline was mixed and reacted with phosgene to give N-cyclohexyl-N-(3-trifluoromethylphenyl)-carbamyl chloride.

PREPARATION 9.—N-CYCLOHEXYL-N-(p-CHLOROPHENYL)-CARBAMYL CHLORIDE

Using the method of Preparation 2, N-cyclohexyl-p-chloroaniline was mixed and reacted with phosgene to give N-cyclohexyl-N-(p-chlorophenyl)-carbamyl chloride.

PREPARATION 10.—N-CYCLOPENTYL-N-(o-CHLOROPHENYL)-CARBAMYL CHLORIDE

Using the method of Preparation 2, N-cyclopentyl-o-chloroaniline was mixed and reacted with phosgene to give N-cyclopentyl-N-(o-chlorophenyl)-carbamyl chloride.

PREPARATION 11.—N-PHENYLCARBAMYL CHLORIDE

Using the method of Preparation 1, aniline was mixed and reacted together with phosgene to produce N-phenylcarbamyl chloride.

PREPARATION 12.—N-(4-METHOXYPHENYL) CARBAMYL CHLORIDE

Using the method of Preparation 1, 4-methoxy-aniline was mixed and reacted together with phosgene to produce N-(4-methoxyphenyl)carbamyl chloride.

PREPARATION 13.—N-(4-CHLOROPHENYL) CARBAMYL CHLORIDE

Using the method of Preparation 1, 4-chloro-aniline was mixed and reacted together with phosgene to produce N-(4-chlorophenyl)carbamyl chloride.

PREPARATION 14.—N-(1-NAPHTHYL)CARBAMYL CHLORIDE

Using the method of Preparation 1, 1-naphthylamine was mixed and reacted together with phosgene to produce N-(1-naphthyl)carbamyl chloride.

PREPARATION 15.—N,N-DIMETHYLCARBAMYL CHLORIDE

Using the method of Preparation 1, dimethylamine was mixed and reacted with phosgene to produce N,N-dimethylcarbamyl chloride.

PREPARATION 16.—N-METHYL-N-CYCLOHEXYL-CARBAMYL CHLORIDE

Using the method of Preparation 1, N-methyl-cyclohexylamine was mixed and reacted together with phosgene to produce N-methyl-N-cyclohexylcarbamyl chloride.

PREPARATION 17.—N,N-DIETHYLCARBAMYL CHLORIDE

Using the method of Preparation 1, diethylamine was mixed and reacted together with phosgene to produce N,N-diethylcarbamyl chloride.

PREPARATION 18.—INDOLINOCARBONYL CHLORIDE

Using the method of Preparation 1, indoline was reacted with phosgene to produce 1-indolinocarbonyl chloride.

PREPARATION 19.—1-(1,2,3,4-TETRAHYDRO-QUINOLINO)CARBONYL CHLORIDE

Using the method of Preparation 1, 1,2,3,4-tetrahydroquinoline was reacted with phosgene to form 1-(1,2,3,4-tetrahydroquinolino)carbonyl chloride.

PREPARATION 20.—1-(1,2,3,4,5,6,7,8-OCTAHYDRO-QUINOLINO)CARBONYL CHLORIDE

Using the method of Preparation 1, 1,2,3,4,5,6,7,8-octahydroquinoline was reacted with phosgene to produce 1-(1,2,3,4,5,6,7,8-octahydroquinolino) carbonyl chloride.

PREPARATION 21.—1-PHENOTHIAZINOCARBONYL CHLORIDE

Using the method of Preparation 2, the sodium salt of phenothiazine (prepared from phenothiazine and sodium amide in toluene) was reacted with phosgene to produce 1-hepnothiazinocarbonyl chloride.

PREPARATION 22.—1-(2,6-DIMETHYLMORPHOLINO)CARBONYL CHLORIDE

Using the method of Preparation 1, 2,6-dimethylmorpholine was reacted with phosgene to produce 1-(2,6-dimethylmorpholino)carbonyl chloride.

Where the foregoing preparations produce a compound having a methyl or other lower-alkyl group, it is to be understood that compounds containing other lower-alkyl groups of straight or branched nature, such as methyl, ethyl, propyl, isopropyl, butyl, sec.-butyl, t.-butyl, amyl, isoamyl, hexyl, heptyl, and octyl, are prepared in the same manner by substitution in the process of the appropriate different lower-alkyl starting material. Likewise, where chloro or other halogen atom is present, although chlorine is preferred, further halogen compounds including iodo, bromo, chloro, and fluoro compounds are prepared starting from the appropriate halogenated starting material. Similarly, where methoxy or other lower-alkoxy group is present, other lower-alkoxy groups containing various lower-alkyl groups having up to eight carbon atoms inclusive are prepared in the same manner from the appropriate different lower-alkoxy starting material. Moreover, when one dilower-alkylamino group, such as the dimethylamino group, is present in a compound, other dilower-alkylamino compounds are prepared in the same manner starting only with the selected different dilower-alkylamino compound. In the same manner, ortho and meta substituted compounds are produced instead of the para by utilizing the selected ortho or meta substituted starting compound. Similarly, other molecular changes are readily made.

The following examples are given by way of illustration only and are not to be construed as limiting.

Example 1.—1-methyl-3-pyrrolidyl N-methyl-N-phenylcarbamate maleate

The sodium salt of 1-methyl-3-pyrrolidinol (0.3 mole) was prepared by refluxing and mechanically stirring an equimolar mixture of 1-methyl-3-pyrrolidinol and sodium amide in toluene solvent until ammonia was no longer evolved. A toluene solution of crude N-methyl-N-phenylcarbamyl chloride (56.2 grams, 0.3 mole) was added and the reaction mixture was stirred and refluxed overnight, cooled and aqueous sodium hydroxide was added to the reaction mixture. The toluene layer was separated, washed with water until the washings were neutral, dried over anhydrous sodium sulfate, filtered, and the filtrate concentrated. The residue was distilled at reduced pressure, yield 50 percent; boiling point 115–117 degrees at 0.002 millimeter; N.E. calculated, 234.29, found, 235.3. The maleate salt was obtained by dissolving 23.4 grams (0.1 mole) of the free base and 11.6 grams (0.1 mole) of maleic acid in 100 milliliters of 2-propanol. Isopropyl ether was added until the solution became turbid and crystallization initiated. The material was recrystallized from a 2-propanol/isopropyl ether mixture. The maleate salt is a white, water soluble, crystalline solid of melting point 87–88.5 degrees centigrade.

Example 2.—1-methyl-3-pyrrolidyl N-ethyl-N-phenylcarbamate

Using the method of Example 1, the sodium salt of 1-methyl-3-pyrrolidinol was mixed and reacted together with N-ethyl-N-phenylcarbamyl chloride to produce 1-methyl-3-pyrrolidyl N-ethyl-N-phenylcarbamate.

Example 3.—1-methyl-3-pyrrolidyl N-(n-propyl)-N-phenylcarbamate

Using the method of Example 1, the sodium salt of 1-methyl-3-pyrrolidinol was mixed and reacted together with N-(n-propyl)-N-phenylcarbamyl chloride to produce 1-methyl-3-pyrrolidyl N-(n-propyl)-N-phenylcarbamate.

Example 4.—1-methyl-3-pyrrolidyl N-cyclopentyl-N-phenylcarbamate

Using the method of Example 1, the sodium salt of 1-methyl-3-pyrrolidinol was mixed and reacted together with N-cyclopentyl-N-phenylcarbamyl chloride to produce 1-methyl-3-pyrrolidyl N-cyclopentyl-N-phenylcarbamate.

Example 5.—1-methyl-3-pyrrolidyl N-(cyclopentyl)-N-phenylcarbamate maleate

Using the method of Example 1, 1-methyl-3-pyrrolidyl-N-(cyclopentyl)-N-phenylcarbamate was mixed and reacted together with maleic acid to produce 1-methyl-3-pyrrolidyl N-(cyclopentyl)-N-phenylcarbamate maleate.

Example 6.—1-methyl-3-pyrrolidyl N-cyclohexyl-N-phenylcarbamate maleate

Using the method of Example 1, the sodium salt of 1-methyl-3-pyrrolidinol was mixed and reacted together with N-cyclohexyl-N-phenylcarbamyl chloride, and the result-

Example 10.—1-methyl-3-pyrrolidyl N-cyclohexyl-N-(3-trifluoromethylphenyl)-carbamate maleate

Using the method of Example 9, the sodium salt of 1-methyl-3-pyrrolidinol was mixed and reacted together with N-cyclohexyl-N-(3-trifluoromethylphenyl)-carbamyl chloride to form 1-methyl-3-pyrrolidyl-N-cyclohexyl-N-(3-trifluoromethylphenyl)-carbamate free base. The free base was subsequently reacted with maleic acid to form 1-methyl-3-pyrrolidyl N-cyclohexyl-N-(3-trifluoromethylphenyl)-carbamate maleate.

Table I below lists the properties of the compounds of Examples 1-10.

ing product subsequently mixed and reacted with maleic acid to form 1-methyl-3-pyrrolidyl N-cyclohexyl-N-phenylcarbamate maleate.

Example 7.—1-methyl-3-pyrrolidyl N-cyclopentyl-N-(p-chlorophenyl)-carbamate maleate

Using the method of Example 1, the sodium salt of 1-methyl-3-pyrrolidinol was mixed and reacted together with N-cyclopentyl-N-(p-chlorophenyl)-carbamyl chloride, and the resulting product subsequently mixed and reacted with maleic acid to form 1-methyl-3-pyrrolidyl N-cyclopentyl-N-(p-chlorophenyl)-carbamate maleate.

Example 8.—1-methyl-3-pyrrolidyl N-cyclohexyl-N-(p-chlorophenyl)-carbamate maleate

Using the method of Example 1, the sodium salt of 1-methyl-3-pyrrolidinol was mixed and reacted together with N-cyclohexyl-N-(p-chlorophenyl)-carbamyl chloride, and the resulting product subsequently mixed and reacted with maleic acid to form 1-methyl-3-pyrrolidyl N-cyclohexyl-N-(p-chlorophenyl)-carbamate maleate.

Example 9.—1-methyl-3-pyrrolidyl N-cyclopentyl-N-(3-trifluoromethylphenyl)-carbamate maleate

A chloroform solution of 0.2 mole of crude N-cyclopentyl-N-(3-trifluoromethylphenyl)-carbamyl chloride was added to a toluene solution of 0.15 mole of the sodium salt of 1-methyl-3-pyrrolidinol with stirring. The sodium salt of the pyrrolidinol was prepared in the same manner as described in Example 1. The reaction mixture was stirred and refluxed overnight, cooled, washed with aqueous 3N sodium hydroxide and water, dried over sodium sulfate, concentrated and the residue distilled under reduced pressure. Boiling point; 145-148 degrees centigrade at 0.005 millimeter. Yield, 29 percent. N.E. calculated, 356.38, found, 357. The maleate salt was prepared in the same manner as described in Example 1 and melted after recrystallization at 96-98.5 degrees centigrade. Yield of the salt from the free base was 85 percent.

40 Using the method of Example 1, the sodium salt of 1-isopropyl-3-pyrrolidinol was mixed and reacted together with N-phenylcarbamyl chloride to form 1-isopropyl-3-pyrrolidyl N-phenylcarbamate.

Example 12.—1-methyl-3-pyrrolidyl N-(4-methoxyphenyl)carbamate

45 Using the method of Example 1, the sodium salt of 1-methyl-3-pyrrolidinol was mixed and reacted together with N-(4-methoxyphenyl)carbamyl chloride to produce 1-methyl-3-pyrrolidyl N-(4-methoxyphenyl)carbamate.

Example 13.—1-methyl-3-pyrrolidyl N-(4-chlorophenyl)carbamate

55 Using the method of Example 1, the sodium salt of 1-methyl-3-pyrrolidinol was mixed and reacted together with N-(4-chlorophenyl)carbamyl chloride to produce 1-methyl-3-pyrrolidyl N-(4-chlorophenyl)carbamate.

Example 14.—1-methyl-3-pyrrolidyl N-(1-naphthyl)carbamate

60 Using the method of Example 1, the sodium salt of 1-methyl-3-pyrrolidinol was mixed and reacted together with N-(1-naphthyl)carbamyl chloride to produce 1-methyl-3-pyrrolidyl N-(1-naphthyl)carbamate.

Example 15.—1-(2-pyridyl)-3-pyrrolidyl N-(4-chlorophenyl)carbamate

65 Using the method of Example 1, the sodium salt of 1-(2-pyridyl)-3-pyrrolidinol was mixed and reacted together with N-(4-chlorophenyl)carbamyl chloride to produce 1-(2-pyridyl)-3-pyrrolidyl N-(4-chlorophenyl)carbamate.

70 Table II below lists the properties of the compounds of Examples 11-15.

TABLE II

Ex.	M.P. (B.P. ° C./mm.)	Empirical For- mula (Mol. Wt.)	C Percent Cal'd. Found	H Percent Cal'd. Found	N Percent Cal'd. Found

Example 16.—1-isopropyl-3-pyrrolidyl N,N-dimethylcarbamate hydrochloride

Using the method of Example 1, the sodium salt of 1-isopropyl-3-pyrrolidinol was mixed and reacted together with N,N-dimethylcarbamyl chloride to form the free base of 1-isopropyl-3-pyrrolidyl-N,N-dimethylcarbamate. The free base was subsequently reacted with hydrochloric acid to form 1-isopropyl-3-pyrrolidyl N,N-dimethylcarbamate hydrochloride.

Example 17.—1-methyl-3-pyrrolidyl N-methyl-N-cyclohexylcarbamate maleate

Using the method of Example 1, the sodium salt of 1-methyl-3-pyrrolidinol was mixed and reacted together with N-methyl-N-cyclohexylcarbamyl chloride to form the free base of 1-methyl-3-pyrrolidyl N-methyl-N-cyclohexylcarbamate. The free base was subsequently reacted with maleic acid to form 1-methyl-3-pyrrolidyl N-methyl-N-cyclohexylcarbamate maleate.

Example 18.—1-methyl-3-pyrrolidyl N,N-diethylcarbamate

Using the method of Example 1, the sodium salt of 1-methyl-3-pyrrolidinol was mixed and reacted together with N,N-diethylcarbamyl chloride to produce 1-methyl-3-pyrrolidyl N,N-diethylcarbamate.

Table III below lists the properties of the compounds of Examples 16-18.

TABLE III

Ex.	M.P. ° C. (B.P. ° C./mm.)	Empirical For- mula (Mol. Wt.)	C Percent Cal'd. Found	H Percent Cal'd. Found	N Percent Cal'd. Found

Example 19.—1-methyl-3-pyrrolidyl indolinocarboxylate maleate

Using the method of Example 1, the sodium salt of 1-methyl-3-pyrrolidinol was mixed and reacted together with indolinocarbonyl chloride to form the free base of 1-methyl-3-pyrrolidyl indolinocarboxylate. The free base was subsequently reacted with maleic acid to form 1-methyl-3-pyrrolidyl indolinocarboxylate maleate.

Example 20.—1-methyl-3-pyrrolidyl 1-(1,2,3,4-tetrahydroquinolino)carboxylate maleate

Using the method of Example 1, the sodium salt of 1-methyl-3-pyrrolidinol was mixed and reacted together with 1-(1,2,3,4-tetrahydroquinolino)carbonyl chloride to produce the free base of 1-methyl-3-pyrrolidyl 1-(1,2,3,4-tetrahydroquinolino)carboxylate. The free base was subsequently reacted with maleic acid to form 1-methyl-3-pyrrolidyl 1-(1,2,3,4-tetrahydroquinolino)carboxylate maleate.

Example 21.—1-methyl-3-pyrrolidyl 1-octahydroquinolinocarboxylate maleate

Using the method of Example 1, the sodium salt of 1-methyl-3-pyrrolidinol was mixed and reacted together with 1-octahydroquinolinocarbonyl chloride to produce the free base of 1-methyl-3-pyrrolidyl 1-octahydroquinolinocarboxylate. The free base was subsequently reacted with maleic acid to form 1-methyl-3-pyrrolidyl 1-octahydroquinolinocarboxylate maleate.

Example 22.—1-methyl-3-pyrrolidyl 1-phenothiazinocarboxylate maleate

Using the method of Example 1, the sodium salt of 1-methyl-3-pyrrolidinol was mixed and reacted together with 1-phenothiazinocarbonyl chloride to produce the free base of 1-methyl-3-pyrrolidyl 1-phenothiazinocarboxylate. The free base was subsequently reacted with maleic acid to form 1-methyl-3-pyrrolidyl 1-phenothiazinocarboxylate maleate.

acid to form 1-methyl-3-pyrrolidyl 1-phenothiazinocarboxylate maleate.

Example 23.—1-methyl-3-pyrrolidyl 1-(2,6-dimethylmorpholino)carboxylate

Using the method of Example 1, the sodium salt of 1-methyl-3-pyrrolidinol was mixed and reacted together with 1-(2,6-dimethylmorpholino)carbonyl chloride to

* Basic N.

produce 1-methyl - 3 - pyrrolidyl 1-(2,6-dimethylmorpholino)carboxylate.

Table IV above lists the properties of the compounds of Examples 19-23.

Where the foregoing examples produce a compound having a methyl or other lower-alkyl group, it is to be understood that compounds containing other lower-alkyl groups of straight or branched nature, such as methyl, ethyl, propyl, isopropyl, butyl, sec.-butyl, t.-butyl, amyl, isoamyl, hexyl, heptyl, and octyl, are prepared in the same manner by substitution in the process of the appropriate different lower-alkyl starting material. Likewise, where chloro or other halogen atom is present, although chlorine is preferred, further halogen compounds including iodo, bromo, chloro, and fluoro compounds are prepared starting from the appropriate halogenated starting material. Similarly, where methoxy or other lower-alkoxy group is present, compounds having other lower-alkoxy groups containing various lower-alkyl groups having up to eight carbon atoms inclusive are prepared in the same manner from the appropriate different lower-alkoxy starting material. Moreover, when one dilower-alkylamino group, such as the dimethylamino group, is present in a compound, other dilower-alkylamino compounds are prepared in the same manner starting only with the selected different dilower-alkylamino compound. In the same manner, ortho and meta products are produced instead of the para by utilizing the selected ortho or meta substituted starting material. Similarly, other molecular changes within the scope of the invention are readily made.

The compounds of the invention are generally characterized by the pharmacological activity hereinbefore stated, making them useful in counteracting certain physiological abnormalities in a living animal body. Effective quantities of the pharmacologically active compounds of the invention may be administered to a living animal body in any one of various ways, for example, orally as in capsules or tablets, parenterally in the form of sterile solutions, suspensions, or by pellet implantation, and in some cases intravenously in the form of sterile solutions. Other modes of administration are cutaneous, subcutaneous, buccal, intramuscular, and intraperitoneal.

Pharmaceutical formulations are usually prepared from a predetermined quantity of one or more of the compounds of the invention, preferably in solid form. Such formulations may take the form of powders, elixirs, solutions, pills, capsules, pellets, or tablets, with or without, but preferably with, any one of a large variety of pharmaceutically acceptable vehicles or carriers. When in admixture with a pharmaceutical vehicle or carrier, the active ingredient usually comprises from about 0.01 to about 75 percent, normally from about 0.05 to about 25 percent, by weight of the composition. Carriers such as starch, sugar, talc, commonly used synthetic and natural gums, water, and the like, may be used in such formulations. Binders such as gelatin, and lubricants such as sodium stearate, may be used to form tablets. Disintegrating agents such as sodium bicarbonate may also be included in tablets.

Although relatively small quantities of the active materials of the invention, even as low as 0.1 milligram, may be used in cases of administration to subjects having a relatively low body weight, unit dosages are usually five milligrams or above and preferably twenty-five, fifty, or one-hundred milligrams or even higher, depending of course upon the subject treated and the particular result desired. Usual broader ranges appear to be one to 200 milligrams per unit dose. The active agents of the invention may be combined for administration with other pharmacologically active agents, such as analgesics, sedatives, tranquilizers, adrenal or progestational or estrogenic steroids or hormones, or the like, or with buffers, antacids or the like, and the proportion of the active agent or agents in the compositions may be varied

widely. It is only necessary that the active ingredient of the invention constitute an effective amount, i.e., such that a suitable effective dosage will be obtained consistent with the dosage form employed. Obviously, several unit dosage forms may be administered at about the same time. The exact individual dosages as well as daily dosages in a particular case will of course be determined according to well-established principles under the direction of a physician or veterinarian.

Example 24.—Formulations

The following formulations are representative for all of the pharmacologically active compounds of the invention, but have been particularly designed to embody as the active ingredient 1-methyl-3-pyrrolidyl N-cyclopentyl-N-phenylcarbamate in the form of an acid addition salt thereof, e.g., the maleate.

A. Capsules

Capsules of 2.5 milligrams, 10 milligrams, 25 milligrams, and 50 milligrams of active ingredient per capsule were prepared. With the higher amounts of active ingredient, reduction may be made in the amount of lactose.

	Per capsule,	milligrams
25	Blend for encapsulation:	
	1. 1 - methyl - 3 - pyrrolidyl N-cyclopentyl-N-phenylcarbamate maleate	2.5
	2. Lactose	299.2
	3. Starch	129.0
	4. Magnesium stearate	4.3
	Total, milligrams	435.0

The active ingredient, the lactose, the starch, and the magnesium stearate are uniformly blended and encapsulated.

B. Tablets

I. A typical formulation for a tablet containing 5.0 milligrams of active ingredient per tablet follows. The formulation may be used for other strengths of active ingredient, in this case 1-methyl-3-pyrrolidyl N-cyclopentyl-N-phenylcarbamate maleate, by adjustment of the weight of dicalcium phosphate.

	Per tablet,	milligrams
45	Formulation for tablet:	
	1. 1 - methyl - 3 - pyrrolidyl N-cyclopentyl-N-phenylcarbamate maleate	5.0
	2. Corn starch	13.6
	3. Corn starch (paste)	3.4
	4. Lactose	79.2
	5. Dicalcium phosphate	68.0
	6. Calcium stearate	0.9
	Total, milligrams	170.1

55 Uniformly blend 1, 2, 4, and 5. Prepare 3 as a ten percent paste in water. Granulate the blend with starch paste and pass the wet mass through an eight-mesh screen. The wet granulation is dried and sized through a twelve-mesh screen. The dried granules are blended with the calcium stearate and compressed.

60 II. An additional tablet formulation containing a higher dosage of 1-methyl-3-pyrrolidyl N-cyclopentyl-N-phenylcarbamate maleate is prepared as follows:

	Per tablet,	milligrams
65	Ingredients:	
	1. 1 - methyl - 3 - pyrrolidyl N-cyclopentyl-N-phenylcarbamate maleate	50.0
	2. Lactose	90.0
	3. Milo starch	20.0
	4. Corn starch	38.0
	5. Calcium stearate	2.0
	Total, milligrams	200.0

70 Uniformly blend 1, 2, 3, and 4. This blend is granulated using water as a granulating medium. The wet

granules are passed through an eight-mesh screen and dried at 140 to 160 degrees Fahrenheit overnight. The dried granules are passed through a ten-mesh screen and blended with 5, and this blend is then converted into tablets using a suitable tablet press.

C. Injectable 2.5 percent sterile solution

Ingredients: Per cubic centimeter

1. 1-methyl-3-pyrrolidyl N-cyclopentyl-N-phenylcarbamate maleate, milligrams	25
2. Preservative, e.g., chlorobutanol, percent weight/volume	0.5
3. Water for injection, q.s.	

Prepare solution, clarify by filtration, fill into vials, seal and autoclave.

It is to be understood that the invention is not to be limited to the exact details of operation or exact compounds, compositions, or procedures shown and described, as obvious modifications and equivalents will be apparent to one skilled in the art, and the invention is therefore to be limited only by the scope of the appended claims.

I claim:

1. A compound selected from (a) those having the formula:

wherein R is a lower-alkyl radical having 1 to 4 carbon atoms inclusive,

wherein R' is selected from the group consisting of methyl and hydrogen, a maximum of two R' being methyl,

wherein A is a radical selected from the group consisting of lower-alkyl having 1 to 6 carbon atoms, inclusive, and lower-cycloalkyl having 3 to 9 carbon atoms, inclusive, and

wherein A' is a monocarbocyclic aryl group having a maximum of fifteen carbon atoms selected from the group consisting of phenyl, trifluoromethylphenyl, lower-alkoxyphenyl, dilower-alkylaminophenyl, lower-alkylphenyl, and halophenyl, and (b) pharmaceutically acceptable acid addition salts thereof.

2. A pharmaceutically acceptable acid addition salt of a 1-lower-alkyl-3-pyrrolidyl N-lower-alkyl-N-arylcaramate wherein the 1-lower-alkyl group has 1 to 4 carbon atoms, inclusive, wherein the N-lower-alkyl group has 1 to 6 carbon atoms, inclusive, and wherein the aryl group is a monocarbocyclic aryl group having a maximum of fifteen carbon atoms selected from the group consisting of phenyl, trifluoromethylphenyl, lower-alkoxyphenyl, dilower-alkylaminophenyl, lower-alkylphenyl, and halophenyl.

3. A pharmaceutically acceptable acid addition salt of a 1-lower-alkyl-3-pyrrolidyl N-lower-cycloalkyl-N-arylcaramate wherein the lower-alkyl group has 1 to 4 carbon atoms, inclusive, wherein the lower-cycloalkyl group has 3 to 9 carbon atoms, inclusive, and the aryl group is a monocarbocyclic aryl group having a maximum of fifteen carbon atoms selected from the group consisting of phenyl, trifluoromethylphenyl, lower-alkoxyphenyl, dilower-alkylaminophenyl, lower-alkylphenyl, and halophenyl.

4. A 1-lower-alkyl-3-pyrrolidyl N-lower-alkyl-N-phenylcarbamate pharmaceutically acceptable acid addition salt wherein the 1-lower-alkyl group has 1 to 4 carbon atoms, inclusive, and wherein the N-lower-alkyl group has 1 to 6 carbon atoms, inclusive.

5. A 1-methyl-3-pyrrolidyl N-methyl-N-phenylcarbamate pharmaceutically acceptable acid addition salt.

6. A 1-methyl-3-pyrrolidyl N-(n-propyl)-N-phenylcarbamate pharmaceutically acceptable acid addition salt.

7. 1 - lower-alkyl-3-pyrrolidyl N-cycloalkyl-N-phenylcarbamate wherein cycloalkyl has up to a maximum of nine carbon atoms and "lower-alkyl" has 1 to 4 carbon atoms, inclusive.

8. A 1-lower-alkyl-3-pyrrolidyl N-cycloalkyl-N-phenylcarbamate pharmaceutically acceptable acid addition salt wherein cycloalkyl has up to a maximum of nine carbon atoms and "lower-alkyl" has 1 to 4 carbon atoms, inclusive.

9. 1 - methyl-3-pyrrolidyl N-cyclopentyl-N-phenylcarbamate.

10. A 1-methyl-3-pyrrolidyl N-cyclopentyl-N-phenylcarbamate pharmaceutically acceptable acid addition salt.

11. A 1-methyl-3-pyrrolidyl N-cyclohexyl-N-phenylcarbamate pharmaceutically acceptable acid addition salt.

12. A 1-lower-alkyl-3-pyrrolidyl N-cycloalkyl-N-chlorophenyl-carbamate pharmaceutically acceptable acid addition salt wherein cycloalkyl has up to a maximum of nine carbon atoms and wherein "lower-alkyl" has 1 to 4 carbon atoms, inclusive.

13. A 1-methyl-3-pyrrolidyl N-cyclopentyl-N-(p-chlorophenyl)-carbamate pharmaceutically acceptable acid addition salt.

14. A 1-methyl-3-pyrrolidyl N-cyclohexyl-N-(p-chlorophenyl)-carbamate pharmaceutically acceptable acid addition salt.

15. A 1 - lower-alkyl-3-pyrrolidyl N-cycloalkyl-N-trifluoromethylphenylcarbamate pharmaceutically acceptable acid addition salt wherein cycloalkyl has up to a maximum of nine carbon atoms and wherein "lower-alkyl" has 1 to 4 carbon atoms, inclusive.

16. A 1 - methyl-3-pyrrolidyl N-cyclopentyl-N-(3-trifluoromethylphenyl)-carbamate pharmaceutically acceptable acid addition salt.

17. A 1 - methyl-3-pyrrolidyl N-cyclohexyl-N-(3-trifluoromethylphenyl)-carbamate pharmaceutically acceptable acid addition salt.

18. A compound selected from (a) those having the formula:

wherein R is selected from the group consisting of a lower-alkyl radical having 1 to 4 carbon atoms, inclusive, and 2-pyridyl,

wherein R' is selected from the group consisting of methyl and hydrogen, a maximum of two R' being methyl,

wherein A' is a monocarbocyclic aryl group having a maximum of fifteen carbon atoms selected from the group consisting of phenyl, trifluoromethylphenyl, lower-alkoxyphenyl, dilower-alkylaminophenyl, lower-alkylphenyl, naphthyl and halophenyl, and (b) pharmaceutically acceptable acid addition salts thereof.

19. A compound selected from (a) those having the formula:

wherein R is a lower-alkyl radical having 1 to 4 carbon atoms, inclusive,

wherein R' is selected from the group consisting of methyl and hydrogen, a maximum of two R' being methyl, and

wherein both A and A' are selected from the group consisting of lower-alkyl having 1 to 6 carbon atoms,

17

inclusive, and lower-cycloalkyl having 3 to 9 carbon atoms, inclusive, and (b) pharmaceutically acceptable acid addition salts thereof, at least one of A and A' being lower-cycloalkyl.

20. A compound selected from (a) those having the formula:

wherein R is a lower-alkyl radical having 1 to 4 carbon atoms, inclusive,

wherein R' is selected from the group consisting of methyl and hydrogen, a maximum of two R' being methyl, and

wherein

forms a member having 4 to 12 carbon atoms, inclusive, selected from the group consisting of indolino, tetrahydroquinolino, phenothiazino, octahydroquinolino, morpholino, thiamorpholino, pyrrolidino, piperidino, piperazino, and lower-alkylpiperazino, and (b) pharmaceutically acceptable acid addition salts thereof.

21. A compound selected from (a) those having the formula:

15

25

30

35

18

wherein R is selected from the group consisting of a lower-alkyl radical having 1 to 4 carbon atoms, inclusive, and pyridyl,

wherein R' is selected from the group consisting of methyl and hydrogen, a maximum of two R' being methyl,

wherein A is selected from the group consisting of hydrogen, lower-alkyl having 1 to 6 carbon atoms, inclusive, and lower-cycloalkyl having 3 to 9 carbon atoms, inclusive, and

wherein A' is selected from the group consisting of a monocarbocyclic aryl group containing a maximum of fifteen carbon atoms selected from the group consisting of phenyl, trifluoromethylphenyl, lower-alkoxyphenyl, dilower-alkylaminophenyl, lower-alkylphenyl, halophenyl and naphthyl, and, when A is lower-cycloalkyl, lower-alkyl having 1-6 carbon atoms inclusive, and lower-cycloalkyl having 3-9 carbon atoms, inclusive,

and wherein A and A' together with the nitrogen atom forms a member having 4-12 carbon atoms inclusive, selected from the group consisting of indolino, tetrahydroquinolino, phenothiazino, octahydroquinolino, morpholino, thiamorpholino, pyrrolidino, piperidino, piperazino, and lower-alkylpiperazino, and (b) pharmaceutically acceptable acid addition salts thereof.
